(57) CLAIM

The ornamental design for a pet collar, as shown and described.

DESCRIPTION

FIG. 1 is a front view of a pet collar, showing my new design;

FIG. 2 is a top view thereof;

FIG. 3 is a rear view thereof;

FIG. 4 is a bottom view thereof;

FIG. 5 is a right side view thereof;

FIG. 6 is a left side view thereof;

FIG. 7 is a top, front perspective view thereof; and,

FIG. 8 is a top, rear perspective view thereof.

In the drawings, the broken lines depict elements of the pet collar that form no part of the claimed design.
